Specification for Design.

Patented Aug. 30, 1921.

Application filed March 17, 1921. Serial No. 453,161. Term of patent 14 years.

To all whom it may concern:

Be it known that I, PATRICK J. McHUGH, a citizen of the United States of America, and resident of Cincinnati, in the county of Hamilton and State of Ohio, have invented a new, original, and ornamental Design for a Vehicle-Tire, of which the following is a specification, reference being had to the accompanying drawing, forming part thereof.

Fig. 2 is a sectional view on line 2—2 of Fig. 1.

I claim:

The ornamental design for a vehicle tire, as shown.

PATRICK J. McHUGH.
